UNITED STATES PATENT OFFICE

2,050,063

REFRIGERATED STORE WINDOW

Arthur T. Millott, Euclid, Ohio, assignor to General Electric Company, a corporation of New York

Application March 7, 1935, Serial No. 9,766

12 Claims. (Cl. 62—89.5)

My invention relates to cooling apparatus for display compartments.

Perishable articles, such as cuts of meat, are frequently exhibited to prospective purchasers in various types of display compartments, which may be either in the form of a display case located inside of a store or a display window located in the front of the same facing the sidewalk. It is desirable to provide apparatus for cooling such articles in order to preserve them, so that they will remain salable and retain an attractive appearance. A display compartment of this type is usually closed and is provided with a transparent front panel. A cooling unit is provided to cool the air in the compartment, the cooled air being circulated over the perishable articles displayed. Since the temperature of the air on the outside of the transparent front panel is usually relatively high the apparatus must be arranged to prevent sweating of this front panel.

It is an object of my invention to provide a display compartment having a cooling apparatus so arranged that cooled air is supplied to and surrounds articles displayed in the compartment and in which a minimum amount of cooled air for this purpose is required.

It is a further object of my invention to avoid frosting or condensation on the transparent panel of a display compartment.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing, in which, Fig. 1 is a perspective view, partly in section, of an ordinary store-front display window equipped with a cooling apparatus embodying my invention, and Fig. 2 is a transverse sectional view of a display window, similar to the one shown in Fig. 1, equipped with a modified form of cooling apparatus embodying my invention.

Referring to the drawing, in Fig. 1 I have shown a store-front display window embodying my invention and including a closed compartment 10 provided with a transparent front panel 11 made of plate glass, or the like, which is mounted in the front wall 12 of a store building. A separable casing 13, which is open at the top is provided, having a heat insulated floor and side walls within the compartment 10, in order to reduce the absorption of heat from the sup-

porting structure and the surrounding air. A cooling unit 14 is mounted in the lower part of the casing 13 on legs 15, in order to provide a space at the bottom of the cooling unit 14 for the admission of air thereto. In this embodiment of my invention, the cooling unit 14 includes a finned coil type evaporator, which is connected to a compressor and condenser unit located in any convenient place near the compartment 10. Other cooling units similar to the cooling unit 14 may be placed at spaced intervals along the base of the compartment 10, if required to obtain the necessary refrigeration capacity.

I have provided a baffle and shelf arrangement above the cooling unit 14, which is so constructed that articles to be displayed are supported in a position to be readily viewed through the transparent front panel, while at the same time the current of cooled air from the cooling unit is directed over them. This baffle and shelf construction, which assists in directing the movement of the cooling air, as hereinafter described, includes an L-shaped baffle 16 supported on the top of the cooling unit 14. Terraced shelves 17 and 18, for articles to be displayed, are supported by the L-shaped baffle 16 and by a vertical support 19, the latter being supported at its ends by the end walls of the casing 13. The terraced shelves 17 and 18 are arranged at such an angle that the articles carried thereon will be readily visible through the front panel 11. These shelves are of open wirework construction, thus presenting openings in the surfaces thereof for the circulation of cooling air through them and over the articles supported thereon. The adjacent edges, of the shelves 17 and 18, are supported on the flanges formed by the angle irons 19a and 19b, respectively. The angle irons 19a and 19b are welded, or otherwise secured, to the upper and lower edges of the vertical support 19, respectively, the angle iron 19a having a rearwardly extending portion on which the front edge of the shelf 17 is supported, and the lower angle iron 19b having a forwardly projecting portion on which the rear edge of the shelf 18 is supported. Perforations are provided in a vertical support 19 to direct the circulation of cooling air over the adjacent shelves. A second perforated vertical support 20 is connected to the end walls of the casing 13 and to the upper rear edge of the L-shaped baffle 16. The vertical support 20 is provided with angle irons 20a and 20b which are welded, or otherwise secured, to the upper and lower edges of the ver-

tical support 20, respectively. The upper angle iron 20a has a rearwardly extending portion on which the front edge of a wire shelf 21 is supported. A lower angle iron 20b has a forwardly extending portion on which the rear edge of the shelf 17 is supported. The rear edge of the shelf 21 is supported on an angle iron 16a welded, or otherwise secured, to the rear wall of the casing 13. An angle iron 16a is welded, or otherwise secured, to the front edge of the L-shaped baffle 16 and supports the front edge of the shelf 18. The lower front edge of the L-shaped baffle 16 is connected to the insulating casing 13 by a perforated support 22, the upper edge of which is hooked over the upstanding portion of the angle iron 16a.

The air in the compartment 10 is positively circulated through the cooling unit 14 by a fan, or other forced draft apparatus therein, and in passing over the heat absorbing surface of the cooling unit 14 is cooled thereby. Cooled air is discharged downwardly from an aperture in the bottom of the cooling unit 14 and divides into two divergent streams upon striking the bottom of the casing 13, as indicated by the arrows 23 and 24. The stream of air indicated by the arrow 23 passes toward the rear of the casing 13 and moves upwardly along the rear wall thereof through the wire shelf 21. It will be noted that the L-shaped baffle 16 assists in thus directing the moving air. After passing through the shelf 21, the air is drawn downwardly through the shelf 17 into the inlet of the cooling unit 14. The inlet of the cooling unit 14 is provided with a grille 25 which registers with an aperture 26 formed in the horizontal portion of the L-shaped baffle 16. The air discharged from the cooling unit 14 and circulating as described thus completes an orbital circuit from the cooling unit through the shelves 21 and 17, and about the articles supported thereon, back to the cooling unit. The stream of air, discharged from the cooling unit 14 and indicated by the arrow 24, passes through a similar orbital circuit; that is, it moves upwardly through the apertures in the support 22 and is drawn across the articles supported on the shelf 18, through the apertures in this shelf and back to the inlet of the cooling unit 14. As indicated by the arrows in Fig. 1, some of the air passing over the shelves 17 and 18 passes through the apertures provided in the vertical support 19 and then downwardly to the inlet of the cooling unit 14. It is desirable to divide the cooled air into a plurality of streams, as described above, since the velocity of the circulating air may be reduced to one-half, for example, by dividing it into two streams, while at the same time an equal volume of cooled air is provided for each shelf. It is advantageous to utilize cooled air moving at a relatively low velocity, since the dehydration of the articles to be cooled may be somewhat reduced in this manner.

Store-front display windows of the type illustrated are usually relatively high and when equipped with cooling apparatus, in accordance with my invention, a stratum of relatively warm air will remain in the top of the compartment 10. Since it is lighter than the stratum of artificially cooled air in the lower portion of the compartment, it will have no natural tendency to move downward and displace the same. The orbital movement of the cooled air in paths closely adjacent the articles to be cooled, as described above, is especially adapted to maintain this stratified condition of the air in the compartment,

ment, since a minimum amount of disturbance is thus created. The disturbance of the stratum of warm air is also minimized by the use of a plurality of streams of cool air since the latter may be circulated at low velocity as explained above. As a consequence, only a part of the air in the compartment 10 need be passed through the cooling unit 14, in order to maintain the articles on display, at a sufficiently low temperature for preservation purposes, and economy is thus much improved. Also, since air is a comparatively poor conductor of heat, the stratum of still warm air in the upper part of the compartment 10 serves to insulate the upper walls thereof, so that the insulated casing 13 need be extended only a short distance above the display shelves.

Some of the cooled air passing downwardly over the shelf 18 and through the perforated support 22 would ordinarily strike the transparent front panel 11 and since the exterior air is at a relatively higher temperature than the cooled air, the latter would tend to cause the condensation of moisture on the front panel 11, that is sweating thereof. I avoid sweating of the front panel 11 in this manner, by providing a transparent baffle 27, which is mounted in the front edge of the insulating casing 13 and which extends across in spaced relation to the lower portion of the transparent front panel 11. It is desirable that the transparent baffle 27 should extend upward only about half of the vertical height of the terraced shelves 17, 18 and 21, both in order to economize material and in order that an observer standing outside the transparent front panel 11 will be able to view the articles displayed on the terraced shelves with unobstructed vision. In addition to the advantages noted the use of such a baffle is to be preferred over a multiple glass window in that it may be easily installed with a cooling unit in available display compartments without modifying the construction of the latter.

In Fig. 2 I have shown a modified form of cooling apparatus embodying my invention, which is supported in a store-front display window having a closed compartment 30 provided with a transparent front panel 31. The compartment 30 is provided with a separable insulating casing 32 having insulation in the walls of the base and side walls thereof, in order to prevent the absorption of heat from the supporting structure and surrounding air. A fin coil type cooling unit 33 is mounted in the lower part of the compartment 30 on the base of the insulating casing 32. The baffle and shelf construction, which I have shown in this modification of my invention, is preferably made of sheet metal and includes a Z-shaped member 34. The lower portion 34a of the member 34 forms a vertical baffle extending entirely across the casing 32 between the side walls thereof, and is provided with an aperture in the lower portion thereof, closely surrounding the cooling unit 33, the baffle 34a being otherwise imperforate. The intermediate portion of a Z-shaped member 34 forms an imperforate shelf 35, and the upper portion thereof forms a vertical perforated baffle 36, which is secured to the lower edge of a forwardly extending portion 32a of the insulating casing 32. A second imperforate shelf 37, arranged in terraced relation with respect to the shelf 35, is formed by a sheet metal member 38, which extends across the casing 32, and is secured at the upper rear edge of the vertical baffle 34a. The lower front portion of the member 38 forms a perforated baffle 39. The lower front edge of the baffle 38 is welded, or

otherwise secured, to the casing 32. The lower front edges of the shelves 35 and 37 are provided with raised portions 40 and 41, respectively, for retaining the platters 42 and 42a containing perishable articles to be displayed in position thereon.

Air, in the closed compartment 30, is circulated therein by a fan contained in a casing 43, which is mounted on one end of the cooling unit 33. The fan in the casing 43 draws air through the cooling unit 33 where it is cooled by passing across the heat absorbing surfaces thereof, the cooled air then being discharged in the direction indicated by the arrows 44. The cooling unit 33 may be of the same type as the cooling unit 14, described above. The cooled air, discharged from the cooling unit 33, through the fan casing 43, passes upwardly along the rear wall of the casing 32 and is deflected outwardly through the louvres 45 formed in the perforated baffle 36 by the projecting portion 32a of the casing 32. The louvres 45, in the vertical support or baffle 36, direct the cooled air downwardly over the articles supported on the shelves 35 and 37 and, after passing over these shelves, the air enters the louvres 46 formed in the lower perforated support 39. The air passing through the louvres 46 is drawn into the cooling unit 33, along the path indicated by the arrows 47, by the fan contained in the casing 43. The orbital path of the cooling air is thus completed.

A transparent baffle 48 is provided, which extends across the lower portion of the transparent front panel 31 and spaced therefrom, thus preventing the sweating of the latter by contact with the cooled air passing downwardly over the shelves 35 and 37 into the louvres 46. Since the cooling air is caused to move in an orbital path, as described above, a stratum of warm air in the upper portion of the compartment 30, and a stratum of circulating artificially cooled air in the lower portion of the compartment 30 are maintained.

While I have shown particular embodiments of my invention, I do not desire my invention to be limited to the particular construction shown and described, and I intend in the appended claims to cover all modifications within the spirit and scope of my invention.

What I claim as new and desire to secure by Letters Patent of the United States is:

1. A relatively high closed display compartment of the store-front type having a transparent front panel, a separable open top heat insulating casing in said compartment having bottom front rear and side walls, the upper edge of said front wall of said casing extending adjacent the lower edge of said transparent front panel, means extending substantially across said open top heat insulating casing for supporting articles in said compartment in a position to be readily visible through said transparent front panel, said compartment having a stratum of relatively warm air in the upper part thereof, and means located in the lower portion of said heat insulating casing for cooling a stratum of air in the lower portion of said compartment and for positively circulating said stratum of artificially cooled air in an orbital path about said supporting means to cool articles placed thereon.

2. A relatively high, closed display compartment of the store-front type having a transparent front panel, a separable open top heat insulating casing in said compartment having bottom front rear and side walls, the upper edge of said front

wall extending adjacent the lower edge of said transparent front panel, a cooling unit supported in the lower part of said compartment, supporting means including a series of terraced shelves located above said cooling unit extending substantially across the open top heat insulating casing for supporting articles at such an angle with respect to said transparent front panel as to be readily visible therethrough, a plurality of vertical supports between said shelves, at least one of said supports being perforated to facilitate the passage of cooled air across an adjacent shelf, means for positively circulating air transversely of said compartment over the heat absorbing surfaces of said cooling unit, and then over articles carried on said supporting means, and means including a transparent baffle extending across the lower portion only of said transparent front panel and supported on the upper portion of said front wall of said heat insulating casing for deflecting cooled air approaching said transparent front panel to prevent sweating thereof.

3. A relatively high, closed display compartment of the store-front type having a transparent front panel, a heat insulating casing covering the floor and lower part of the side walls of said compartment, the upper edge of the front wall of said insulating casing extending adjacent the lower edge of said transparent front panel, a cooling unit supported in the lower part of said compartment, supporting means including a series of terraced shelves located above said cooling unit for supporting articles at such an angle with respect to said transparent front panel as to be readily visible therethrough, means for positively circulating air transversely of said compartment over the heat absorbing surfaces of said cooling unit and then over articles carried on said supporting means, means including a transparent vertical baffle extending across the lower portion of said transparent front panel and less than half the height of said shelves for deflecting cooled air approaching said transparent front panel to prevent sweating thereof, and means for supporting said transparent baffle adjacent the top of the front wall of said insulating casing.

4. A relatively high, closed display compartment of the store-front type having a transparent front panel, a separable open top heat insulating casing in said compartment having bottom front rear and side walls, the upper edge of said front wall of said heat insulating casing extending adjacent the lower edge of said transparent front panel, said compartment having a stratum of relatively warm air in the upper part thereof, a cooling unit located in said compartment, means for supporting articles in said compartment in a position to be readily visible through said transparent front panel, means for positively circulating air in the lower portion of said compartment over the heat absorbing surfaces of said cooling unit and then directing said air over articles carried on said first mentioned supporting means, and means including a transparent baffle extending across only the lower portion of said transparent front panel and supported in the upper portion of said front wall of said heat insulating casing for deflecting cooled air approaching the same to prevent sweating thereof.

5. A relatively high, closed display compartment having a transparent front panel, said compartment having a stratum of relatively warm air in the upper part thereof, means including a cooling unit located in said compartment for creat-

- ing a stratum of cooled air in the lower portion of said compartment, means for supporting articles in said compartment in a position to be readily visible through said transparent front panel, 5 means for positively circulating air in said compartment over the heat absorbing surfaces of said cooling unit, means for dividing said cooled air into a plurality of divergent streams and then directing the same over articles carried on said 10 first mentioned means, and means including a transparent baffle extending across only a portion of said transparent front panel for deflecting cooled air approaching the same to prevent sweating thereof.
- 15 6. A closed display compartment having a transparent front panel, a cooling unit supported in the lower part of said compartment, an L-shaped baffle located above said cooling unit and having an opening therein registering with 20 the top of said cooling unit, supporting means providing for the circulation of air therethrough and located above said cooling unit for supporting articles at such an angle with respect to said transparent front panel as to be readily visible 25 therethrough, means for positively circulating air transversely of said compartment over the heat absorbing surfaces of said cooling unit and then over articles carried on said supporting means, and means including a transparent baffle extending across the lower portion only of said transparent front panel for deflecting cooled air approaching the same to prevent sweating thereof.
7. A relatively high, closed display compartment having a transparent front panel, said compartment having a stratum of relatively warm air in the upper part thereof, a cooling unit supported in the lower part of said compartment, means for supporting articles above said cooling unit and in a position to be readily visible through said 35 transparent front panel, means for positively circulating cooled air over the heat absorbing surfaces of said cooling unit and for creating a stratum of cooled air in the lower portion of said compartment, means for directing cooled air 40 from said cooling unit outwardly toward the side walls of said compartment in a plurality of divergent streams across articles supported on said first mentioned means and back to the inlet of said cooling unit, and means including a transparent baffle extending across the lower portion 45 only of said transparent front panel for deflecting cooled air approaching the same to prevent sweating thereof.
8. A closed display compartment having a transparent front panel, a cooling unit supported in the lower part of said compartment and having an air inlet in the top thereof, an L-shaped baffle located above said cooling unit and having an opening therein registering with said air inlet, supporting means including a series of 50 terraced shelves located above said cooling unit for supporting articles at a sufficient angle with respect to said transparent front panel to be readily visible therethrough, a plurality of vertical supports between said shelves, at least one of said supports being perforated to facilitate the passage of cooled air across an adjacent shelf, means for positively circulating air from said cooling unit upwardly past the longitudinal edges of said 55 L-shaped baffle, across said shelves and downwardly to said inlet of said cooling unit, and means including a transparent baffle extending across the lower portion only of said transparent front panel for deflecting cooled air in approaching the same to prevent sweating thereof.
9. A closed display compartment having a transparent front panel, a cooling unit supported in the lower part of said compartment and having an air inlet in the top thereof, an L-shaped baffle supported on the top of said cooling unit 5 and having an opening therein registering with said air inlet, a shelf providing for the circulation of air therethrough and extending forwardly and downwardly from the rear edge of said baffle, a second shelf providing for the circulation of 10 air therethrough and extending backwardly and upwardly from the front edge of said baffle, a vertical support extending between the adjacent edges of said shelves, said vertical support being perforated to facilitate the passage of cooled air 15 across said shelves, means for positively circulating air from said cooling unit upwardly past the longitudinal edges of said L-shaped baffle, across said shelves and downwardly to said inlet of said cooling unit, and means including a transparent baffle extending across the lower portion only of said transparent front panel for deflecting cooled air approaching the same to prevent sweating thereof.
10. A closed display compartment having a transparent front panel, a cooling unit supported in the lower part of said compartment, a baffle extending vertically upward from the top of said cooling unit, supporting means carried by said baffle for supporting articles at such an angle 30 with respect to said transparent front panel as to be readily visible therethrough, means for positively circulating air transversely of said compartment over the heat absorbing surfaces of said cooling unit and then over articles carried on 35 said supporting means, said last mentioned means including a baffle located above said supporting means for directing cooled air downwardly over said supporting means, and means including a transparent baffle extending across the lower portion 40 only of said transparent front panel for deflecting cooled air approaching the same to prevent sweating thereof.
11. A closed display compartment having a transparent front panel, a cooling unit supported in the lower part of said compartment, a baffle extending about said cooling unit and vertically upward therefrom, vertically displaced shelves extending from said baffle on each side thereof, a vertical baffle located above the rear edge of 50 the uppermost shelf and provided with a series of louvres for directing cooled air downwardly across said shelves, and means including a transparent baffle extending across the lower portion 55 only of said transparent front panel for preventing contact between said downwardly directed cooled air and said transparent front panel.
12. A closed display compartment having a transparent front panel, a cooling unit supported in the lower part of said compartment, a baffle extending about said cooling unit and vertically upward therefrom, vertically displaced inclined shelves extending from said baffle on each side thereof, a vertical baffle located above the rear edge of the uppermost shelf and provided with a series of louvres for directing cooled air downwardly across said shelves, and means including a transparent baffle extending across the lower portion 65 only of said transparent front panel for preventing contact between said downwardly directed cooled air and said transparent front panel.

CERTIFICATE OF CORRECTION.

Patent No. 2,050,063.

August 4, 1936.

ARTHUR T. MILLOTT.

It is hereby certified that error appears in the printed specification of the above numbered patent requiring correction as follows: Page 1, second column, line 20, for "aid" read air; page 3, second column, line 67, claim 4, for "in" read on; and that the said Letters Patent should be read with these corrections therein that the same may conform to the record of the case in the Patent Office.

Signed and sealed this 29th day of September, A. D. 1936.
